(57) CLAIM

The ornamental design for a truck bed cover, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever. FIG. 1 is a right-side elevation view showing the environment of a truck.

FIG. 2 is a top perspective view of a truck bed cover; FIG. 3 is a right-side perspective view thereof; FIG. 4 is a left-side perspective view thereof; FIG. 5 is a rear perspective view thereof; FIG. 6 is a front perspective view thereof; FIG. 7 is a top perspective view thereof; and, FIG. 8 is a bottom perspective view thereof, with all of the inner surfaces forming no part of the claimed design. The broken lines shown in the drawings represent portions of the truck bed cover that form no part of the claimed design.

1 Claim, 6 Drawing Sheets
